(57) **CLAIM**

The ornamental design for a cigarette pack with sachet attached on the rear wall of the pack, as shown and described.

DESCRIPTION

FIG. 1 is a rear perspective view of a first embodiment of a cigarette pack with sachet attached on the rear wall of the pack, showing our new design;

FIG. 2 is a front elevational view thereof;

FIG. 3 is a right side elevational view thereof, the left side elevational view being a mirror image duplicate;

FIG. 4 is a top plan view thereof, the bottom plan view being identical;

FIG. 5 is a rear elevational view thereof;

FIG. 6 is a rear perspective view of a second embodiment of a cigarette pack with sachet attached on the rear wall of the pack, showing our new design;

FIG. 7 is a front elevational view thereof;

FIG. 8 is a right side elevational view thereof, the left side elevational view being a mirror image duplicate;

FIG. 9 is a top plan view thereof, the bottom plan view being identical; and,

FIG. 10 is a rear elevational view thereof.
